SHEET METAL SLITTER

Fred L. MacQuarrie, Los Angeles, Calif.

Application March 24, 1950, Serial No. 151,648

9 Claims. (Cl. 164—61)

My invention relates to a strip and sheet metal slitter and resides particularly in an improvement in the design of a slitter and combination of new and novel features rendering the slitter far more efficient and capable of slitting much wider coils or sheets of metal than heretofore practical.

A large number of industries and manufactured products require coils of relatively narrow high precision metal strip stock. It is the general practice in rolling this material on the rolling mills to use the maximum width coils possible commensurate with the size and width of the mill. After the rolling operation, it is also general practice where narrower widths than those rolled are required, to run the wide coils through a slitting machine which slits the aforementioned wide coils into specified multiple widths and in so doing maintain high precision throughout the coil or sheet length.

To describe a slitter in its simplest form would be to place two shafts or arbors parallel one above the other. On these shafts or arbors are disposed circular knives of suitable diameter and thickness and held apart from each other on each shaft or arbor by suitable spacers and shims, the width that the knives are separated by the spacers and shims being the approximate width of the finished strips required. These shafts or arbors are supported on bearings at each end. It therefore follows that the wider the strip or sheet required to be slit the greater the stress on the shafts or arbors, particularly at the center where the maximum strain or spring takes place and where the aforementioned shafts or arbors are supported at each end only. Due to the stresses set up as described in the foregoing, it has been the general custom and practice in designing slitters to increase the diameter of the shafts or arbors as the width of material to be slit increased in order to reduce the spring in the shafts or arbors. When this is done it is also necessary to increase the diameter of the knives and spacers with consequent additional large expense due to the high cost of these precision tools. Even with the increase in diameter of the shafts or arbors, spring is not eliminated but merely reduced. Under such conditions precision slitting becomes a problem.

It has long been the desire of the slitting industry to have a slitting machine which will slit material of any input width and up to the maximum gauge in thickness, with a minimum of spring or distortion in the shafts or arbors; which is the main cause of inaccuracy and damage to the edges of the material being slit. It is, therefore, one of the objects of my invention to produce a slitter which will slit coils of strip or sheet stock up to or in excess of 90" without permitting any spring or sag in the shafts or arbors carrying the slitting knives.

It is also among the objects of my invention to provide a slitting machine capable of handling stock of much wider width than heretofore possible without increasing the size of the shafts or arbors. It would therefore be possible to use smaller diameter slitting knives and spacers, thereby materially decreasing the cost of such a machine. It would therefore follow that where there are several slitting machines in an industry it would be possible to standardize the size of the slitting knives and spacers so that they would be interchangeable on all machines, thereby effecting a further saving in inventory and cost of these items.

In addition to the conventional housing bearings at each end of the shafts or arbors, this slitter is equipped with additional auxiliary adjustable heavy duty roller

2

bearing units, both top and bottom, between the main bearings supporting the shafts or arbors. These are carried in a heavy cast double truss on top and by a special trussed cast base on the bottom. This is in effect equivalent to a four-high mill arrangement in separating force and its effect in reducing spring. Any number of these units may be used and same can be placed as close as 3" apart along the shafts or arbors.

For instance, if these units were placed 9" apart on a 36" wide slitter, it would be equivalent in support to four nine inch slitters between housings. These auxiliary units may be placed in any suitable position along the shafts or arbors and held in place by an ingenious cam locking device. These units are interchangeable and may be used either on top or bottom.

Each unit consists of a block housing machined from solid steel. Mounted within this block is the adjusting screw and roll housing for vertical adjustment. The adjustable roll housing is also machined from a solid steel block. Each roll housing contains three accurately ground hardened rolls mounted on roller bearings. These rolls ride on special hardened and precision ground spacers. Adjustment of vertical screw on each unit permits changing knives without removing units from a setup position.

In addition to reducing spring to a minimum these units also serve in reducing the capital and replacement cost; as smaller shafts or arbors, knives and spacers may be used.

Another outstanding feature is the guides and rest bar arrangement. This arrangement consists of top and bottom rest bars on both the entry and delivery side. These run the full width of the slitter. They are set but 3" from the vertical center of the shafts or arbors on each side. This results in a span of only 6" for finger guides as compared to as much as 24" on conventional slitters. Rest bars are fully adjustable to obtain the closest possible clearance as related to the slitter knives and steel, which is necessary for good slitting.

This design also eliminates the necessity of using expensive specially made guides. All guides used, both finger and fill-in, are cut to width from $\frac{3}{4}$ " hardwood boards. Therefore, short span finger guides do not ride on the spacers. Both sides of the finger guides can, therefore, be used.

Most slitters, particularly when used in connection with power slitting embody a pair of pinch rolls, that is, a pair of cooperable rolls positioned ahead of the slitting knives adapted to feed the stock into the knives. Such pinch rolls are, as a rule, driven by the same electric motor or source of power as the shafts or arbors, upon which the knives are mounted, and are consequently run at the same angular speed as the slitting knives. It is, therefore, apparent that the slitting knives must be identical in relative diameter with the pinch rolls or that some means must be provided for quickly and effectively releasing the pinch rolls so that they will either free-wheel or be released entirely in order to prevent the metal being slit from buckling between the pinch rolls and the slitting knives.

In view of the cost of the slitting knives, they are reground when they become dull rather than being replaced. It is apparent that any appreciable amount of re-grinding will change the effective diameter of the knives, thereby causing a different lineal travel on the periphery of the knives as related to the pinch rolls.

It is also one of the objects of my invention to provide means for instantaneously releasing the pinch rolls after the stock has been fed into the knives and onto the reel.

Further additional means for completely immobilizing the action of the pinch rolls by separating same has been incorporated in my design.

It is also among the objects of my invention to produce a slitter having numerous new and novel details of construction which add to the over-all efficiency of the slitter, which tend to increase the life of the slitter thereby reducing the cost of maintenance, and which result in a more satisfactory operation.

Other and further objects and advantages of my invention will become apparent from the drawings and the specifications relative thereto.

In the drawings:

Figure 1 is a partial back elevation of a slitter embodying the principles of my invention.

Figure 2 is an end elevation of the slitter shown in Figure 1 taken from the left.

Figure 3 is a sectional view taken on line 3—3 of Figure 1.

Figure 4 is an enlarged plan sectional view taken on line 4—4 of Figure 1.

Figure 5 is an elevational sectional view taken on line 5—5 of Figure 4.

Figure 6 is an enlarged detailed sectional view taken on line 6—6 of Figure 5.

Figure 7 is a sectional view taken on line 7—7 of Figure 5.

Figure 8 is an enlarged detail sectional view of the upper portion of Figure 7.

Figure 9 is a sectional view taken on line 9—9 of Figure 8.

Figure 10 is an end sectional elevation taken on line 10—10 of Figure 5.

Figure 11 is an end elevational section taken on line 11—11 of Figure 5.

Figure 12 is an enlarged detailed fragmentary plan view of the guide members and controls.

Figure 13 is a sectional view taken on line 13—13 of Figure 12.

Figure 14 is a section taken on line 14—14 of Figure 7.

Figure 15 is a fragmentary sectional view of the locking device taken on line 15—15 of Figure 9.

Figure 16 is a fragmentary detail of a quick releasing mechanism for the pinch rolls.

The embodiment of my invention chosen for purposes of illustration in the drawings is composed of two main divisions, the feeding mechanism and the slitting mechanism. For purposes of clarity and simplification, each of these elements will be treated separately and the details discussed in connection therewith.

FEEDING MECHANISM

The feeding mechanism is composed of three essential elements, namely, an entry roll assembly designated generally 20 (Figure 7), a pinch roll assembly designated generally 21, and a guide roll assembly designated generally 22.

Entry roll assembly

The entry roll assembly 20 is composed of two complementary parts, each of which comprises a pair of vertically disposed cylindrical rolls 25 and 26 rotatably disposed by means of bearings 27 and 28 (Figure 14) in an L-shaped frame 29 having a cap 30 secured to the top thereof by means of a cap screw or bolt 31. The foot of the frame 29 rests on a plate 32 formed with a longitudinal groove 33. It will be understood that the width of the groove 33 corresponds with the width of the foot of the frame 29 and is adapted to prevent lateral displacement of the roll assembly.

The plate 32 is also formed with a longitudinal slot 34 having an undercut or wider section 35. The foot of the frame 29 is formed with a plurality of apertures 36 adapted to receive nut-and-bolt assemblies 37 and 38. The heads 39 and 40 are disposed in the undercut portion 35 of the slot 34, it being understood that the width of the slot 34 is less than the width of the head, so that they may not pull through. The heads 39 and 40 are formed with flat sections adapted to engage the sides of the undercut portion 35 to prevent turning. It is, therefore, readily apparent that upon tightening the nut-and-bolt assemblies 37 and 38, the frame 29 will be held securely in position.

The plate 32 is secured to a frame member 42 which is a part of the general framework of the apparatus.

It will be understood that the entry roll assembly, such as is shown in detail in Figure 14, is duplicated, that is, there is one on each side of the slitter and it is adapted to guide the sheet stock as it is being fed into the pinch rolls preparatory to slitting and to prevent lateral displacement thereof.

Pinch roll assembly

The pinch roll assembly 21 (as illustrated in Figure 7) is also composed of complementary parts, each of which comprises a pair of upright legs 51 and 52 secured to the frame by means of nut-and-bolt assemblies, such as 53, and is provided with a head member 54 secured to the upright posts 51 and 52 by means of the bolts 55 and 56.

The head member 54 is formed with an internally threaded boss 57 adapted to receive a threaded shaft 58 having a control handle 59 disposed on the top thereof. A bearing block 60 is slidably disposed between the posts 51 and 52. A compression spring 61 is disposed between the bearing block 60 and a pressure plate 62. The shaft 58 abuts against the pressure plate 62 so that by rotation of the shaft 58 threading it downwardly through the head 54, a greater pressure is applied to the bearing block 60 by means of the compression spring 61.

A stationary bearing block 63 is also disposed between the posts 51 and 52.

It will be understood that the mounting means just described is duplicated on each side of the slitting machine and is provided with bearing blocks in axial alignment with the bearing blocks 60 and 63.

A pair of pinch rolls 64 and 65 are rotatably disposed in or between the complementary bearing blocks. The roll 64 is free-wheeling, by that is meant, it has no source of power directly connected thereto; whereas, the roll 65 is connected with a source of power, the details of which are illustrated in Figure 4.

The bottom roll 65 is coupled with a shaft 67 having one-half 68 of a split clutch slidably but non-rotatably disposed thereon, the other half 69 of the split clutch being non-rotatably, non-slidably secured to the end of a shaft 70. The shaft 70 is supported by pillow blocks 71 and 72 and carries a sprocket 73 which is connected by means of a chain 74 to a sprocket 75. The sprocket 75 is non-rotatably secured to a shaft 76 which has disposed thereon in slidable non-rotatable engagement one-half 77 of a split clutch. The other half 78 of the split clutch is secured to a sub-shaft 79 to which is secured sprocket 80, the sprocket 80 being associated with a source of power by means of a chain drive 81.

The split clutch segment 68 is controlled by means of a yoke 82 and a rod 83. The rod 83 extends outwardly to the ends of the slitting machine and has a handle 84 disposed on the end thereof so that lateral displacement of the handle 84 causes a pivoting action on the yoke 82 to engage or disengage the two halves 68 and 69 of the split clutch for engaging or disengaging the rolls 65 from the source of power.

The compression spring 61 bears downwardly on the bearing block 60, thereby urging the roll 64 in cooperation with the roll 65. A sheet of raw stock 85 is fed between the rolls and due to the frictional engagement and the power-driven rotation of the roll 65, is forced to feed therebetween causing rotation of the roll 64. It will readily be apparent that when the roll 64 is raised from contact with the sheet 85, the frictional engagement between the roll 65 and the sheet 85 is lost and the pinch rolls no longer drive the sheet through the slitting operation. A means for quickly releasing the pressure of the roll 64 is provided.

Quick release means

The quick releasing means is shown in detail in Figures 2 and 16. It comprises a pin 90 secured to the bearing block 60, a link 91 which said link is formed with an elongated slot 92 adjacent the lower end thereof, a cam 93 having an eccentric circular boss 94 disposed in a circular aperture 95 in the upper end of the link member 91. The cam 93 is rotatably secured to the head 54 by means of a pin 96 and is rotatable by means of a handle 97.

It will readily be seen that rotation of the cam 93 about the pins 96 will cause an upward movement of the eccentric boss 94, thereby pulling the link member 91 upwardly until the bottom of the slot 92 engages the pin 90 thereby pulling the bearing block 60 upwardly and disengaging the roll 64 from contact with the material 85.

Guide roll assembly

The guide roll assembly 22 (Figures 7, 12 and 13) is positioned between the pinch roll assembly 21 and the slitting knives and is adapted for more accurate adjustment and guiding function than the entry rolls 20.

A plate 100 is secured to the general frame between the pinch rolls and the slitting knives and is formed with a longitudinal dove-tail groove 101. A roll carriage 102 is slidably disposed on the plate 100 and is provided with a dove-tail tongue 103 adapted to slidably fit in the dove-tail groove 101.

The dove-tail tongue 103 is formed with a longitudinal

threaded aperture 104 adapted to receive a shaft 105 in threaded engagement therewith. A handle or turning wheel 106 (Figures 12 and 13) is non-rotatably connected with the outer end of the shaft 105 and is formed with a hub 107. Rotation of the wheel 106 causes rotation of the shaft 105 and because of the threaded engagement between the shaft 105 and the dove-tail tongue 103, causes lateral movement of the carriage 102. It will be noted from Figure 4 that there are oppositely disposed complementary roll carriages designated 22 and 22a.

The shaft 105 is formed with a longitudinal bore 108 through which is disposed a threaded shaft 109. The threaded shaft 109 is in threaded engagement with the opposite roll carriage 22a and extends outwardly beyond the handle 106. The shaft 109 is provided with a handle 110 for rotation thereof.

The threads on one of the shafts and carriages are right-hand while the threads on the other assembly are left-hand. Therefore, rotation of both wheels 106 and 110 in the same direction causes a contraction or expansion of the distance between the roll carriages. Movement of the wheels 106 and 110 in opposite directions causes shifting of the roll carriages either to the right or to the left depending upon the direction of rotation but maintains the respective distance between the rolls.

An L-shaped base 115 formed with a plurality of apertures 116 at one edge thereof is disposed on top of the carriage plate 102, and a cap 117 is secured on the top thereof. The top 117 and the L-shaped base member 115 are secured to the carriage plate 102 by means of a plurality of bolts, such as the bolts 118.

A roll 119 is disposed in each of the apertures 116 by means of a bolt 120 and is freely rotatable therein. The center of rotation of each of the rolls lies on a common line and each of the rolls has a substantial identical diameter so that sheet stock being fed into the slitter will be guided by each of the rolls 119.

SLITTING MECHANISM

The slitting mechanism comprises in general a pair of end frames designated generally 135 and 136 (Figures 1 and 5) adapted to support the slitting rolls designated generally 137 and 138; a truss 139 extending between said frames; and a gear train adapted to deliver power for power rotation of both of said slitting rolls 137 and 138.

End frames

The end frame 135 is slidably disposed on the general frame and is readily removable from the end of the slitting rolls 137 and 138 for repairs or replacement of the slitting knives. The frame 136 is secured to the general frame in a fixed position.

In describing the details of construction of the end frame 135, reference is made to Figure 2 wherein the details are more clearly set forth.

The frame 135 comprises essentially a base 140 having a depending tongue 141 adapted to fit in a longitudinal groove 142 of the base plate 143, a pair of parallel upright legs 145 and 146 formed with complementary bearing surfaces 147 and 148, and a head 149 adjoining the top of the legs 145 and 146. Bearing blocks 150 and 151 are slidably disposed between the bearing surfaces 147 and 148 and are retained in position by means of retaining plates 152 and 153. The bearing block 150 abuts against the upper surface of the base 140. The bearing block 151 is vertically adjustable, the purpose and details of which will be explained later.

Each of the bearing blocks 150 and 151 are formed with parallel bores 155 and 156 (Figure 5), respectively, adapted to receive bearings, such as the double roller bearings 157 and 158. Grease retainer plates 159 and 160 are secured to the bearing blocks over the ends of the respective bores.

The head 149 (Figure 2) is formed with a threaded bore adapted to receive the threaded shaft 162. The bearing block 151 is suspended from the lower end of the shaft 162 so that rotation of the shaft by means of the handle 163 effects a vertical adjustment of the bearing block 151.

The base member 140 is formed with a threaded bore 165 (Figure 5) adapted to receive a threaded shaft 166 having a handle 167 on the outer end thereof. Rotation of the handle 167 causes lateral movement of the frame 135.

Slitting knives

The slitting knife assemblies, designated generally 137 and 138, comprise in detail a pair of parallel shafts 170 and an extension of shaft 76, having bearing journals, such as at 172 and 173, on both ends thereof. Slitting knives, such as 174 and 176, formed as an annulus are disposed over the shafts 170 and 76, respectively, and are spaced apart by spacers 176 and 177. It will be understood that the spacers 176 or 177 are selected as to width to give a proper spacing between the cutting knives to produce the desired thickness or width of the ribbon stock which is the end result of the slitting machine.

The bearing journals 172 are rotatably disposed in the bearings 156 and 157. The bearing journals 173 are supported by bearings 178 and 179, respectively, supported by the end member 136.

End frame

The end member 136 is formed with a pair of upright legs 180 and 181 (Figures 10 and 11) having bearing surfaces on the inner facing edges thereof adapted to receive in sliding relation a housing 182. The housing 182 is supported by and controlled in its vertical position by a threaded shaft 183 threaded through a threaded bore of a head member 184 supported by the upstanding legs 180 and 181. The bearing 178 is carried by the housing 182. The housing 182 is formed with a gear chamber 186 and a bore 187 (Figure 5) in axial alignment with the bearing 178 and is adapted to receive a bearing 188. The shaft 170 extends through the housing 182 and is supported by the bearing 188 so that when the carriage 135 is moved outwardly away from the end 172 of the shaft 170, the bearings 188 and 178 will support the slitting knife assembly.

The shaft 170 has secured thereto in non-rotational engagement by any suitable means, such as keying, a gear 190. The gear 190 is in mesh with a gear 191 which is carried in non-rotational engagement on a shaft 192. A gear 193 is also keyed to the shaft 192 so that the gears 191 and 193 rotate as a unit. The gear 193 is in mesh with an idling gear 195 which in turn meshes with a gear 196. The gear 196 is keyed to the shaft 76. The shaft 76 is connected to the source of power, as previously explained, through the split clutch 77 and 78.

The split clutch 77 being slidably disposed on the shaft 76 is controlled in its axial position by means of a yoke 200, which said yoke is pivoted at point 201 and controlled at its other end by a shaft 202 having a handle 203 on the end thereof. It is clear that displacement of the handle 203 to the left in Figure 4 will cause rotation of the yoke 200 clockwise, thereby disengaging the section 77 from the section 78 of the split clutch.

The gears 190 and 192 are formed with relatively deep teeth so that vertical displacement of the bearing housing 182 will not disengage the mesh of the gears. It is, therefore, possible to obtain a much greater adjustment in the knives permitting knives to be re-ground more times which results in a greater reduction in diameter of the knives. Such an arrangement results in a material saving when the excessive cost of the knives is considered.

Intermediate bearings

In slitting metal, particularly sheet metal having a substantially heavy gauge, relatively large forces are necessarily applied between the opposing slitting knives. Such force has heretofore been the limiting factor in designing the width of the slitter and, hence, the width of the sheet capable of being handled. I have provided and designed a slitter having a relatively wide slitting capacity, hence, a relatively long shaft supporting the slitting knives. Were these shafts unsupported, they would either have to be made excessively larger in diameter or would be subject to considerable displacement at the center thereof due to bending of the shaft. In order to overcome both of these objections, I have provided intermediate bearings for the shaft. As illustrated in Figure 5, I have shown three sets of intermediate bearings, designated generally 210, adapted to support the upper shaft, and three sets of bearings, designated generally 211, adapted to support the lower shaft.

Referring to Figures 8 and 9, each of the support bear-

ings comprises a plurality of rollers 212 rotatably supported on shaft 213 having an axis parallel with the axis of the shaft 170 and adapted to ride on the knife spacers 176.

The rolls 212 are supported by a housing 214 having an upwardly extending boss 215 internally threaded at 216. The boss 215 is formed with a slot 217 adapted to receive a key 218.

A carriage block 219 is formed with an aperture 220 adapted to slidably receive the boss 215, the side wall of which is formed with a slot 221 adapted to receive the key 218 so that the boss 215 cannot rotate in the bore or aperture 220.

A shaft 223 having its lower end threaded is in threaded engagement with the bore 216 so that rotation thereof causes upward or downward movement of the carriage 210 in order to regulate the pressure of the rolls 212 against the spacers 176.

A plate 224 having a bore 225 adapted to receive the shaft 223 is disposed on top of the carriage 219. Thrust collars 226 and 227 are secured to the shaft 223 to prevent upward or downward movement thereof with respect to the carriage 219. It will be understood that the plate 224 is securely fastened to the carriage 219 by means of cap screws or bolts, such as 228.

The carriage 219 is formed with outwardly projecting shoulders 230 and 231 on top and bottom thereof defining a channel therebetween.

The truss previously designated by the general number 139 comprises a pair of channel members 233 and 234 secured between the end carriages 135 and 136, each of which is formed with an inwardly directed tongue 235 and 236 in opposed relation. The tongues 235 and 236 are complementary with the channel defined by the shoulders 230 and 231, so that the carriage member 219 is longitudinally slidable with respect to the truss members 233 and 234.

Locking means

The carriage 219 is formed with a vertical bore 240 (Figure 9) adjacent one of the truss members, such as 233. A horizontal bore 241 and a horizontal slot 242 all intersect at a common point. A stud 243 having a cam 244 non-rotatably secured to the lower end thereof is disposed in the bore 240.

A pin 245 (Figure 15) having a shoulder 246 at the inner end thereof is inserted in the bore 241 and is urged against the cam 244 by means of a coil spring 247. A guide bushing 248 is disposed in the outer end of the bore 241.

It will be seen that rotation of the shaft 243 causes rotation of the cam 244, thereby urging the pin 245 outwardly against the truss member 233 to lock the carriage 219 in position.

Each of the truss members 233 and 234 are formed with horizontal tongues 253 and 254 (see Figure 5) disposed on either end thereof and adapted to fit in a transverse groove 272 and 273 formed in the upper end of the end frames 135 and 136. The truss members are secured to the end frame 136 by means of bolts 249 and are secured to the end frame 135 by means of bolts 250. The bolt 250 is provided with a spacer sleeve 251.

When it is desired to change the cutting knives, the nut 252 is removed and the sleeve 251 taken off the bolt 250 so that the carriage or end frame 135 can be moved laterally to the left in Figure 5. The bolt 250 remains in position to support the trusses 233 and 234.

Guide bars

The end frames, such as the end frame 135 in Figure 7, are provided with vertical side plates 255 and 256, each of which is formed with horizontal flanges 257 and 258, each of the horizontal flanges being formed with a threaded bore adapted to receive adjusting bolts 259 and 260. Guide bars 261 and 262 are positioned adjacent the entry and exit of the upper knives, and guide bars or guide rest bars 263 and 264 as they are frequently known are positioned adjacent the entry and exit of the lower cutting knives. For further details of these guide bars, reference is made to Figure 6.

Each of the guide bars is formed with an oblique face, such as 265, so that the inner lower edge can extend as far as possible inwardly towards the point of tangency of the cutting knives 174 and 175 in order to lend support to the ribbon stock 85 being slit by the knives.

The guide bars adjacent the discharge side of the knives are formed with undercut grooves 266 and 267 adapted to receive guide plates 268 and 269.

The guide plates 268 and 269 are preferably formed of a hard or semi-hard wood which is readily and inexpensively replaceable in the event of excessive wear.

Surface plates 270 and 271 are secured to the guide bars 261 and 263, respectively, the surface plates 270 and 271 being preferably formed of a hardened metal to give a long-wearing surface, but are readily replaceable in the event of excessive wear without replacing the entire guide bar. Thus, it will be seen that the stock 85 being slit by the cutting knives is fully supported throughout the entire slitting machine.

Safety lock

Referring to Figures 1 and 5, it will be noted that the knives 174 and 175 and the spacers 176 and 177 are secured onto the shafts 76 and 170, respectively, by means of split nuts 275 and 276.

After the carriage 135 has been moved outwardly to the left in Figures 1 and 5, the nuts 275 and 276 must be removed in order to re-position the slitting knives. To do this, one or both of the shafts 76 and 170 must be securely held against rotation.

In order to restrain the shafts against rotation, I have provided a collar 280 keyed to the shaft 76.

Referring to Figure 3, it will be noted that the collar 280 is formed with at least one tapered hole 281. A bracket 282 formed with a boss 283 having an internally threaded bore adapted to receive a threaded shaft 285, is secured to the frame.

The shaft 285 is provided with a handle 286 and is associated with a lever 287 adapted to actuate a switch 288.

When the shaft 285 is moved inwardly so that the end thereof projects into the bore 281, the end of the lever 287 is removed from contact with the switch 288 which is the normally off micro-switch, it being understood that the switch 288 is in series with the main source of power to drive the slitter.

The end of the shaft 285 upon being inserted in the bore 281 prevents rotation of the collar 280 and, hence, the shaft 76. However, it is impossible so long as the shaft 285 is in engagement with the bore 281 to energize the motor because the switch 288 has been opened.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. A sheet metal slitter comprising a frame having a base, a stationary horizontal truss joining upper parts of the frame, a pair of upper and lower parallel horizontal shafts mounted at opposite ends in the frame, said shafts being continuous from end to end, one of said shafts having a direct drive thereto, a bearing member at each end of the other shaft having a vertically movable mounting in the frame, and adjusting means for each bearing member adapted to move the bearing member up and down, a gear on said other shaft, an idler gear spaced laterally from said first identified gear and meshing therewith and a gear train from the idler gear to the direct drive, axially shiftable spacers on the shafts and oppositely disposed slitting knives between the spacers arranged in pairs so that the application of shearing force on each strip is in the same vertical direction, a plurality of sets of oppositely disposed independently adjustable auxiliary bearing members, one member of each set having a longitudinally shiftable mounting on the truss and the other member of each set having a longitudinally shiftable mounting on the base, and adjusting means on the auxiliary bearing members in each set adapted to force said auxiliary bearing members into contact with a respective collar on the immediately adjacent shaft midway between the next laterally adjacent slitting knives.

2. A sheet metal slitter comprising a frame having a base, end members on the base and a stationary horizontal truss joining the end members, a pair of upper and lower parallel horizontal shafts mounted at opposite ends

thereof in the frame and continuous from end to end, one of said shafts having a fixed position in said frame and a direct drive thereto, a bearing member at each end of the other shaft having a vertically movable mounting in the frame, and an independent adjusting means for each bearing member on said other shaft adapted to move the bearing member up and down relative to the frame, a gear on said other shaft, an idler gear spaced laterally from said first identified gear meshing therewith and a gear train from the idler gear to the direct drive, axially shiftable spacers on the shafts, a plurality of sets of independently adjustable oppositely disposed auxiliary bearing members, one member of each set being on the base and the other member of said set being on the truss, and on a line passing through the axes of both shafts, and pairs of axially shiftable slitting knives on the respective shafts and between the spacers.

3. A sheet metal slitter comprising a frame having a base and a stationary horizontal truss joining upper parts of the frame, a pair of upper and lower parallel horizontal shafts mounted at opposite ends thereof in the frame and continuous from end to end, one of said shafts having a direct drive thereto, a bearing member at each end of the other shaft, a gear on said other shaft, an idler gear meshing therewith and a gear train from the idler gear to the direct drive, axially shiftable spacers on the shafts and oppositely disposed axially shiftable slitting knives between the spacers, a plurality of sets of independently adjustable auxiliary bearing members oppositely disposed on a line passing through the centers of both shafts and having longitudinally shiftable mountings on the truss on the base, said bearing members being adjustable to positions midway between adjacent bearing members, means adapted to secure said bearing members in the longitudinally shifted position, and adjusting means on each bearing member adapted to force said bearing member into contact with a respective collar on the immediately adjacent shaft.

4. A sheet metal slitter comprising a frame having a base, upwardly directed end members on the base and a stationary horizontal truss joining upper parts of the end members, a pair of upper and lower parallel horizontal shafts mounted at opposite ends thereof in the frame and continuous between said ends, the lower of said shafts having a fixed position in said frame, and a direct drive thereto, a bearing member at each end of the upper shaft having a vertically movable mounting in the respective end member, and adjusting means for each bearing member adapted to move the bearing member up and down in the respective end member, a long tooth gear on said upper shaft, a long tooth idler gear on substantially the same horizontal plane meshing therewith and a gear train from the idler gear to the direct drive, axially shiftable spacers on the shafts, a collar intermediate opposite ends of the spacers, and oppositely disposed axially shiftable slitting knives between the spacers, a plurality of sets of oppositely disposed independently adjustable auxiliary bearing members about midway between each pair of knives having longitudinally shiftable mountings with the mounting of one member of each set being on the horizontal truss and the mounting of the other member of each set being in the base, and adjusting means on each auxiliary bearing member all lying in the same plane as the plane of said first identified adjusting means adapted to force said auxiliary bearing member into contact with the respective collar on the immediately adjacent shaft.

5. A sheet metal slitter comprising a frame having a base and a stationary horizontal truss joining upper parts of the frame, a pair of upper and lower parallel horizontal shafts mounted at opposite ends thereof in the frame and continuous from end to end, one of said shafts having a direct drive thereto, a bearing member at each end of the other shaft having a vertically movable mounting in the frame, and adjusting means for each bearing member adapted to move the end member up and down, a gear on said other shaft, an idler gear spaced laterally from the first identified gear and meshing therewith and a gear train from the idler gear to the direct drive, axially shiftable spacers on the shafts and oppositely disposed axially shiftable slitting knives between the spacers, a plurality of sets of oppositely disposed independently adjustable auxiliary bearing members having longitudinally shiftable mountings respectively on the truss and the base extending throughout the entire lengths of the shafts

and adjusting means on each bearing member adapted to force said auxiliary bearing member into contact with a respective collar on the immediately adjacent shaft, and pairs of upper and lower guide rest bars, one pair being on each side of the horizontal shafts, and separate adjustment means between both the upper and the lower guide rest bars and the frame adapted to move said guide rest bars up and down to conform with the shear line between upper and lower slitting knives.

6. A sheet metal slitter comprising a frame having a base, upwardly directed end members on the base and a fixed horizontal truss joining upper parts of the end members, a pair of upper and lower parallel horizontal shafts mounted at opposite ends thereof in the frame and continuous from end to end, one of said shafts having a fixed position in said frame, and a direct drive thereto, a bearing member at each end of the other shaft having a vertically movable mounting in the respective end member, and adjusting means for each bearing member adapted to move the end member up and down, a gear on said other shaft, an idler gear spaced laterally with respect to said first identified gear meshing therewith and a gear train from the idler gear to the direct drive, laterally shiftable spacers on the shafts and oppositely disposed slitting knives therebetween, a plurality of sets of oppositely disposed independently adjustable auxiliary bearing members having oppositely disposed longitudinally shiftable mountings in alignment with the bearing contact and the center line of the respective shaft with the mounting of one member of each set being on the truss and the mounting of the other member of each set being in the base, and adjusting means on each auxiliary bearing member adapted to force said auxiliary bearing member into contact with a respective collar on the immediately adjacent shaft, and pairs of upper and lower guide rest bars, one pair being on each side of the horizontal shafts and having contiguous portions facing the shafts located within the V-shaped space between opposite slitting knives, separate adjusting means between the upper and the lower guide rest bars and the frame adapted to move said bars up and down to conform with the position of shear between upper and lower slitting knives, and guide plates of relatively soft material extending between the spacers on the opposite shafts and between oppositely disposed pairs of guide rest bars.

7. A sheet metal slitter comprising a frame having a base, a stationary horizontal truss having a longitudinal slot therein and joining upper parts of the frame, said base having a longitudinal slot therein parallel to said first slot, a pair of upper and lower parallel horizontal shafts mounted at opposite ends thereof in the frame and continuous from end to end throughout the length of the slot, one of said shafts having a direct drive thereto, a bearing member on each end of the other shaft having a vertically movable mounting in the frame, and adjusting means for each bearing member adapted to move the bearing member up and down, a gear train from said other shaft to the direct drive, axially shiftable spacing collars on the shafts having slitting knives between the spacing collars, and a plurality of pairs of oppositely located independently adjustable auxiliary bearing members extending throughout the length of the respective slots on the truss and on the base and located intermediate the ends of said shafts, each said auxiliary bearing member comprising a housing, horizontally mounted rollers in the housing adapted to roll in contact with the adjacent spacing collar, a boss on the housing, a roll adapted to receive the boss, said roll being slidably attached within the slotted truss for movement endwise with respect thereto, a plate bolted to the top of the roll and an adjusting screw swivelly mounted in the plate having a threaded connection with the boss and being adapted to move said housing up and down.

8. A sheet metal slitter comprising a frame having a base, means joining upper parts of the frame, a pair of upper and lower parallel horizontal shafts mounted at opposite ends in the frame, said shafts being continuous from end to end, one of said shafts having a drive thereto and the other having a drive connected to said one shaft, a bearing member at each end of one of the shafts having a vertically movable mounting in the frame and adjusting means for each of said bearing members adapted to move said bearing members up and down, axially shiftable spacers on the shafts and pairs of oppositely disposed slitting knives between spacers on the respec-

tive shafts arranged so that the application of shearing force on each strip is in the same vertical direction, a plurality of sets of oppositely disposed independently adjustable auxiliary bearing members, one member of said set being on the frame and the other member of said set being on said frame joining means, one member of each set having a longitudinally shiftable mounting on said frame above the shafts and the other member of each set having a longitudinally shiftable mounting on the frame below the shafts and adjustable means on the auxiliary bearing members in each set adapted to force said auxiliary bearing members into contact with a respective collar on the immediately adjacent shaft midway between the next laterally adjacent slitting knives.

9. A sheet metal slitter comprising a frame having a base and means joining upper parts of the frame, a pair of upper and lower parallel horizontal shafts mounted at opposite ends thereof in the frame and continuous from end to end, one of said shafts having a drive thereto and the other of said shafts being driven from said drive, a bearing member at each end of each said shaft, the bearing members of one of said shafts having an adjustment adapted to shift the location of the axes of the shafts with respect to each other, a plurality of sets of oppositely disposed independently adjustable auxiliary bearing members, one member of each set being on the frame and the other member of said set being on the frame joining means, pairs of oppositely disposed axially shiftable slitting knives on the shafts, and sets of guide rest bars each comprising a pair of upper and lower
